DUPLICATION PROCESS AND MASTER
SHEET FOR USE THEREIN

William J. Champion, Chicago, Ill., assignor to
Ditto, Incorporated, Chicago, Ill., a corporation
of West Virginia

Application November 17, 1941, Serial No. 419,395

10 Claims. (Cl. 101—149.5)

This invention relates to solvent process duplication, and more specifically to a solvent process duplication in which solvent is applied to the design surface of the master copy and need not be applied at all to the copy sheet. The invention includes master sheets adapted for use in the process.

Solvent process duplication generally is characterized by the steps of contacting a master design containing a dyestuff with a succession of copy sheets pre-moistened with a substantially volatile solvent for this dye. On contact some of the dye in the master design is dissolved by the solvent and transferred to each of the successive copy sheets so as to give copies of the master design.

While this process is very convenient and has met with commercial success, it has several disadvantages:

1. It is necessary to moisten with solvent the entire area of the copy sheet. Actually, this solvent is used only on those small portions of the copy sheets which contact the actual dye design on the master. The rest of the solvent performs no function. This waste may amount to as much as 98% and almost invariably exceeds 80% of the total liquid consumed.

2. Under conditions not favoring rapid evaporation of the solvent, an excessive amount of solvent is easily retained in the copy paper, causing continuous diffusion or "blurring" and "striking through" of the copies. This is particularly apparent when copies are run on both sides of the sheets so that these are twice moistened with the solvent.

3. Under conditions favoring rapid evaporation, the large amounts of volatile solvent expelled from the copy sheets will cause obnoxious odors, and even health disturbances.

4. The use of volatile solvents represents a definite fire hazard, particularly in electrically-driven machines.

5. The use of solvent in contact with the various metals in the machine results in progressive corrosion and consequent service and replacement problems.

6. The mechanism required for supplying and regulating the solvent flow is quite complex and expensive.

In some instances solvent has been applied to the under surface of a master sheet instead of to the copy sheets. This method has the same disadvantage outlined above and in addition further disadvantages including the necessity for

complicated mechanism for applying the solvent to the under surface of the master sheet.

Also attempts have been made to apply the solvent to the design surface of the master sheet, but these methods have required complicated and expensive mechanism and have not been entirely satisfactory.

The present invention obviates the above disadvantages of the prior art.

10 According to this invention, the solvent is applied directly to the design surface of the master, which has been treated so that only the dye-carrying parts thereof are receptive to the solvent, and so that the dissolved dye cannot spread or diffuse to parts of the master sheet adjacent the design.

This pre-treatment of the master may be accomplished by applying to the master a fluid which is non-miscible with the said solvent.

15 To illustrate, the process is hereafter described step by step, reference being made to the accompanying drawing of which Fig. 1 represents a master sheet, and Fig. 2 a sectional view of a duplication machine on which the invention is being practiced.

20 A dye-carrying design in mirror reverse is produced on a carrier sheet, for example, by drawing directly or by typing with a typewriter having special reversed type on the keys, or preferable by writing or printing on a sheet the back side of which is adjacent to a dye-carrying transfer sheet. The carrier sheet to which the master design is applied is preferably a paper sheet, but may also be a thin metal sheet having a sandblasted or similarly roughened surface, a similar plastic sheet or the like.

25 The nature of the carrier sheet and of the dye-carrying design, and the way in which these have been obtained, prepared or produced, are unimportant so long as the carrier sheet is adapted to retain the solvent repellent further discussed below and to retain the design; and so long as the design is adapted to give colored impressions or copies when acted upon with a dye solvent and contacted with a succession of copy sheets.

30 The master is then treated to make all non-dye-carrying parts thereof repellent to the dye solvent employed in subsequent steps of the process, as detailed below. This treatment includes application to the master of a liquid which is substantially non-miscible with the said dye solvent, and also a non-solvent for the dyestuff of the master design. The mode of supplying this liquid is non-essential. It may be deposited by

wiping the master with an applicator moistened in the repellent, or by contacting the master with repellent-carrying moistening means such as rollers, wicks or the like, either on the duplicating machines or in a separate operation.

Referring now to the attached sketch, the master 6 which has been moistened with the repellent, is fastened to master holding means 1 on the revolvable drum 2. As the drum is caused to rotate by means well known to the art and not shown in the sketch, the master contacts the solvent-applying roller 3. This roller carries the dye solvent and applies this in a very thin film to the master. The solvent is taken up only by the dye-carrying design, and dissolves and plasticizes this so as to render transferable the surface layer of dye on this design.

The solvent is repelled by all non-dye-carrying parts of the master because these have been treated with the solvent repellent, as described above.

On further rotation of the drum, the master contacts a copy sheet 7 which is being fed between the drum and a lower pressure roller 4 by means known to the art (not shown). On contact, a sufficient amount of dye is transferred from the master to produce a copy on the copy sheet.

This cycle is repeated and copies thus produced until the dye on the master is exhausted. The number of copies obtained depends on the selection of ingredients for the dye-carrying design, the porosity of this design, the composition of the solvent, the quantity of solvent applied, the composition and absorbency of the master sheet and of the copy sheets, and on the pressure between master and copy sheets at the moment of transfer.

Generally, any change tending to increase the amount of dye transferred to each copy sheet will enhance copy brightness and reduce the number of copies obtainable, and vice versa. Most conveniently, the copy brightness and length of run can be selected at will by varying the amount of solvent applied to the master sheet.

The solvent may be furnished by almost any type of mechanism adapted to apply a uniform film of liquid to a moving surface. I prefer to effect this transfer of liquid from a surface traveling at the same rate of speed as that of the master. Therefore, a roller driven by friction with the drum and the master or positively driven to have the same peripheral speed, is a preferred mode of applying the liquid. However, usable results may be obtained also with wick type applicators or the like, although the drag or friction tends to accelerate deterioration or "breaking down" of the master design. The pressure between the various members of the solvent applying and distributing mechanism, and between this and the master, should preferably be adjustable.

In an embodiment not shown in the drawing, the solvent applying roller receives the solvent from a felt roller 5 which in turn is partly immersed in a reservoir containing the solvent but in the particular embodiment shown in the drawing the solvent applying roller 3 is itself partly immersed in the solvent.

Obviously, the solvent may be brought to the surface of the applying roller by a great number of means or devices, including wicks, gravity feed, atomizers or spraying devices, and the numerous types of means used in the printing

arts for applying a thin film of printing ink or the like to a roller which in turn applies it in a very thin film to a moving ink receiving and transferring form, plate, design or the like. The invention is not limited to any particular genera or species of these means.

The solvent may be any liquid or semi-liquid composition which is a solvent or plasticizer for the particular dye contained in the master design. For example, if the dye is a water or spirit soluble dyestuff, such as a Fuchsin, Eosin, Auramin, Rhodamin, methyl or crystal violet, methylene blue, a metamine dye, Victoria green, or the like, then polyhydric liquid dye solvent alcohols such as 2 methyl 2,4 pentane diol are preferred solvents, and nitrated oxygen containing liquid dye solvent hydrocarbon derivatives such as 2 nitro 1 butanol, dye solvent liquid amids such as formamid, esters such as ethyl lactate, and glycol derivatives dye solvents such as diethylene glycol mono ethyl ether and the like, and their mixtures are suitable as solvents. If, for example, an oil soluble dye is used in the master design, then I may use hydrocarbon type solvents such as light mineral oils, preferably high boiling solvent naphthas or the like. Generally oil miscible solvents are suitable for use in conjunction with this type of dye. I prefer to employ solvents which are substantially odorless, have a low volatility, and are adapted to dissolve or plasticize the dye in the master design, although obviously the odor does not influence copy results, and volatile solvents may be used, if the speed of rotation of the drum or the design of the machine is such as to keep the rate of evaporation within economically practical limits.

As the repellent, I may use any composition which is readily imbibed or retained in the non-dye carrying portions of the master sheet, and which is substantially non-miscible with the dye-solvent and is a non-solvent for the dye.

For example, in conjunction with the water or spirit soluble dyes and solvents enumerated above, I prefer to use as repellent a water solution of an electrolyte, such as a solution of calcium chloride, ammonium sulfate, barium nitrate, lead acetate, sodium lactate, and the like, in high enough concentration to reduce the solvency of the water for the other materials mentioned above.

In conjunction with oil soluble dyes and hydrocarbon-type solvents, I may use as the repellent water, glycols, glycerines, solutions of electrolytes or of gums, starches or glues and the like in water.

Shortly, I may use as repellent any liquid composition which can be retained by the master sheet, and is non-miscible with the solvent and a non-solvent for the dye used. To illustrate, the following specific examples are given:

Example I

A master was prepared by typing with a hectograph ribbon of prior art onto a paper sheet. Copies were taken in the device shown in the sketch, using as the solvent 2 methyl 2,4 pentane diol, as the repellent a 10% solution of calcium chloride, and as copy sheets an absorbent sulfite sheet known as "Ditto direct process B."

70

Example II

A master was prepared by the procedure disclosed in Figure 1 and Example 1 of U. S. Patent No. 2,254,483 to Hess and Bjorksten. Copies were taken in the device shown in the sketch, using

as a solvent a mixture of 2 parts by weight of 2 nitro 1 butanol and one part of Carbitol, as repellent a saturated solution of ammonium sulfate, and as copy sheet a sulfite sheet known as "Longrun B."

Example III

A master was prepared by typing through an enamel type coated paper sheet against a conventional direct process type duplication transfer paper. Copies were taken in the device shown in the sketch using a 7% solution of sodium silicate as the repellent, formamid as the solvent, and a sulfite sheet known as "Longrun E" as the copy paper.

Example IV

A master was prepared by typing through a super-calendered coffee bag paper against a duplication transfer paper comprising as the active dye ingredient the stearate of methyl violet. Copies were taken in the device shown in the sketch, using high flash solvent naphtha as the solvent, a 2% solution in water of gum arabic as the repellent, and a sulfite sheet known as "Direct process D" as the copy paper.

Obviously these examples are given only to show, by concrete instances, certain modes in which the invention can be applied. They are not to be construed in any sense of limitation as I realize fully that the ingredients, procedures and devices can be varied within wide limits without departure from the spirit or scope of this invention.

The term "relatively non-volatile solvent" is used in the specification and claims to refer to solvents in which the major part of the solvent has less volatility than ethyl alcohol.

I claim:

1. The method of duplicating which comprises applying to the non-design portions of a master having thereon a design of a soluble dye a coating which is substantially non-absorbent of a solvent for said dye, applying said solvent to the surface carrying the design, and thereafter contacting said surface with a copy sheet.

2. The method of duplicating which comprises applying to a master having a design of a soluble dye a liquid which is substantially non-miscible with a solvent for said dye and a non-solvent for said dye, applying said solvent to the surface carrying the design, and thereafter contacting said surface with a copy sheet.

3. The method of duplicating which comprises applying an aqueous solution of an electrolyte to a master sheet having a design thereon of a soluble dye, applying a solvent to the design surface, and thereafter contacting said surface with a copy sheet.

4. The method of duplicating which comprises applying an aqueous solution of an electrolyte to a master sheet having a design thereon of an alcohol soluble dye, applying a glycol type solvent to the design surface, and thereafter contacting said surface with a copy sheet.

5. The method of duplicating which comprises applying an oil repellent liquid to a master sheet having a design thereon of an oil soluble dye, applying a solvent for said oil dye to the design surface, and thereafter contacting said surface with a copy sheet.

6. In the method of duplicating wherein a solvent is applied to a master copy sheet having a design thereon of a soluble dye, the step of pre-treating said master copy sheet by applying thereto a liquid which is substantially non-miscible with said dye solvent and a non-solvent for the dyestuff of the master design.

7. In the method of duplicating wherein a solvent is applied to a master copy sheet having a design thereon of a soluble dye, the steps which comprise applying a fluid to the master copy sheet which is substantially non-miscible with said solvent and a non-solvent for the dyestuff of the master design, and then applying as the said solvent a relatively non-volatile solvent to said design surface.

8. A master sheet adapted for liquid process duplication, said master comprising a sheet having a design thereon of a soluble dye, the non-design portions carrying a fluid which is substantially a non-solvent for the dye of said design, and non-miscible with a solvent for the dye of said design.

9. A master sheet comprising a sheet having a design thereon of a soluble dye, the non-design portions of the sheet containing a solution of an electrolyte.

10. A master sheet comprising a sheet having a design thereon of a water and alcohol soluble dye, the non-design portions of the sheet containing a solution of an electrolyte.

WILLIAM J. CHAMPION.
